Des. 210,798
Patented Apr. 16, 1968

210,798

STREET LIGHT OR THE LIKE ARTICLE

Clifford Bruce Hewson, Brampton, Ontario, Canada, assignor to E. W. Bliss Company of Canada, Ltd., Georgetown, Ontario, Canada

Filed Apr. 4, 1967, Ser. No. 6,517

Term of patent 14 years

(Cl. D48—31)

FIG. 1

FIG. 2

The fragmentary broken line showing of a support pole in FIGURES 1 and 2 is for illustrative purposes only.

I claim:

The ornamental design for a street light or the like article, substantially as shown and described.
